DESIGN FOR A RAZOR

Octavius Victor Rodrigues, Bridgeport, Conn., assignor to Magazine Repeating Razor Company, New York, N. Y., a corporation of New Jersey

Application October 31, 1940, Serial No. 96,238

Term of patent 14 years

To all whom it may concern:

Be it known that I, Octavius Victor Rodrigues, a subject of the King of England, residing at Bridgeport, county of Fairfield and State of Connecticut, have invented a new, original, and ornamental Design for a Razor, of which the following is a specification, reference being had to the accompanying drawing, forming part thereof.

Fig. 1 is a top plan view of a razor showing my new design;

Fig. 2 is a front view in elevation;
Fig. 3 is a side view in elevation, the opposite side being similar to it except reversed;
Fig. 4 is a rear view in elevation.

I claim:
The ornamental design for a razor, substantially as shown and described.

O. VICTOR RODRIGUES.
